UNITED STATES PATENT OFFICE

ARCHIE G. ELDER, OF SEATTLE, WASHINGTON

REFERENCE HOLDER

Application filed March 24, 1928. Serial No. 264,322.

This invention relates to book-supported lesson or copy holders; and its object is to provide a simple, inexpensively constructed, and efficient device of this character which is adapted to be detachably connected to books of different sizes in such a way as not to interfere with the opening and closing of the same nor to the turning of its leaves; and which is adapted to hold a pamphlet or leaflet in a position to be conveniently read by a reader holding the book which supports the pamphlet holder.

The invention is particularly intended for holding lesson pamphlets or the like containing references to different parts of a text book to which the holder is connected, and in the use of which book the student or reader thereof is obliged to turn its leaves to reach passages of the book cited in the lesson.

Lesson pamphlets are now extensively used for Bible and other religious study, and it is advantageous for the student to have the lesson pamphlet attached to the book in order to have both the pamphlet and the book readily available for reference, one with the other.

It is also advantageous to be able, as in the present invention, to provide means for coupling a lesson pamphlet to a book in a manner which will enable them to be held by one hand of the student, leaving the other hand free for turning the leaves of the book as may be required.

The invention consists in the novel construction, adaptation and combination of parts hereinafter described and claimed.

In the accompanying drawings,—

Figure 1 is a front elevation of a holder embodying my invention, shown applied to a book for holding a lesson pamphlet; Fig. 2 is a fragmentary front elevation of the holder shown in Fig. 1, to a larger scale; Fig. 3 is a sectional view taken substantially on the line 3—3 of Fig. 2; Fig. 4 is a horizontal detail sectional view illustrating the adjustable hinge connections between the main frame members of the holder; and Fig. 5 is a detail sectional view through line 5—5 of Fig. 2.

According to the present invention, the body of a holder comprises two plate members 6, each consisting of a head-portion 7 and two fingers 8 and 9 depending therefrom. The finger 8 is arranged in the plane 55 of the lower portion of the respective head, but the finger 9 is offset forwardly at its juncture with the head, as shown in Fig. 3; the extent of the offset or shoulder being substantially the same as, or very slightly 60 greater than, the thickness of the respective member. The form of the fingers 8 and 9 is preferably as indicated in Fig. 1, the outer finger 8 being slightly longer than the other. Said fingers are slightly enlarged 65 at their lower ends. The plate members 6 are connected to each other from their respective heads 7 by means of an extensible link consisting of two telescopically connected parts 10 and 11.

Ends of the link parts are hingedly connected with the respective heads by the provision of curled extremities 12 of the heads surrounding pintle elements 13 provided at ends of the link-parts as shown in Figs. 2 75 and 4. As shown, link-part 10 is a flattened rectangular tube, in which the complementary part 11 slidably fits, both parts being slightly curved longitudinally, as shown in Fig. 4.

In practice, the fingers 9 of both members are formed or arranged, near their lower ends, to engage leaves of a book in close proximity to the back or binding of the leaves.

Clamping-plates 16 are pivotally and yieldably mounted on the respective heads 7, as follows: Adjacent to the ends of the extensible connecting link, such head carries a forwardly protruding pin or stud 17. 90 The front end of each pin 17 has a threaded opening for receiving a screw 18 having a knurled head 18¹ of larger diameter than the pin, which screw head is recessed, as shown in Fig. 3, to receive an end of a 95 helical spring 19. Each clamping-plate 16 is provided with a slightly elongated aperture through which passes the respective pin 17.

Said springs 19 surround the respective 100

pins 17, between the associated clamping-plates and the screw heads 18¹, to normally press the plates backwardly toward the front faces of the heads 7 of the respective members. The rear end of a spring 19 engages in a small opening provided therefor in the associated clamping-plate, being thereby prevented from entering the aperture provided in the clamping-plate for the pin 17. At its lower end a clamping-plate is provided with a rearwardly directed lug 20, the end of which bears against the face of the head 7 to afford a fulcrum about which the body of the clamping plate is swung. At the central part of the clamping-plate 16 a portion thereof is turned rearwardly to provide a guide-tongue 21 which extends through a slot in the head 7. Said tongue 21 is desirably slightly curved, as shown in Fig. 3, and fits slidably in said slot so as to permit pivotal movement of the clamping-plate about the end of the lug 20, but preventing rotation of the plate about the axis of the pin 17.

25 To facilitate introducing a reference leaflet or pamphlet, as B in Fig. 1, into clamping relation with a member 6, the upper portions of the respective clamping-plate 16 and of the head 7 are desirably curved forwardly. Both the heads 7 and the clamping-plates 16 may have the ornamental wing-like outline shown, or be of any other suitable or desired form.

30 In the use of the holder, the extensible connecting-link, formed by the parts 10 and 11, is first adjusted to a length substantially equal to the thickness of a book A (Fig. 1) on which the holder is to be engaged. The complementary fingers 8 and 9 of both members are then inserted in the book to straddle one or more of the fly-leaves thereof adjoining the respective covers *a*; the fingers 8 being placed between the covers and the fly-leaves, and the fingers 9 positioned to bear 35 against the sides of the fly-leaves opposite those contacted by the fingers 8.

The offsetting of the fingers 9 at their juncture with the respective heads 7 permits each of the fly-leaves to lie substantially in 40 a plane so as not to be marred or injured by the holder. When the holder is properly adjusted, the extensible link 10—11 lies between the book covers *a* and seats upon the top of the "round", so called, comprising the 45 rear portions of all of the leaves of the book, excepting the fly-leaves to which the fingers 8 and 9 are engaged. The holder being thus applied, the book may be opened or closed, and the leaves thereof turned to 50 open at any place throughout the book without interfering with such leaf turning, said extensible link acting to support the entire weight of the holder and its contents upon the body of the book or round thereof. In 55 opening and closing the book the pivotally-

connected holder-members are movable integrally with the respective covers of the book.

After the holder is in place upon the book A, the reference-pamphlet B is opened at a 70 desired place and, thus regulated, the lower portion of the pamphlet is inserted between the clamping-plates 16 and heads 7, at both sides of the holder as indicated in Fig. 1. At such position the lower edge of the 75 pamphlet engages upon the tongues 21, which thus serve as stops for limiting the extent to which the leaves of the pamphlet may enter the clamps.

Because of the forward curvature of the 80 heads 7 and the clamping plates 16, the pamphlet B will be caused to incline slightly forwardly of the plane of the book A when the latter is held vertically; or, if the book is held horizontally, the pamphlet will be held in a relatively upwardly inclined position with respect to the book; and, in any case, when the book is held for the convenient reading thereof, the pamphlet is also held in a correspondingly convenient readable position. The adjustable screws 18, moreover, provide means to regulate the effective power of the springs 19 whereby the springs will regulate the clamping plates 16 to cause the pamphlet B to be held at a selected forwardly angular relation with respect to the book A.

90 The pamphlet clamping members are proportioned to accommodate at either side of the holder one or all the leaves of a pamphlet, so that the latter may be held securely at any place, selectively, at which it is desired to be opened.

95 The pamphlet is removed from the holder when it is desired to turn the leaves thereof, and may be reinserted within the holder after being opened at the desired place. To prevent the holder being accidentally disengaged from the book A when pulling the pamphlet from the clamp-parts, there is provided on each of the heads 7 a rearwardly extending lug 22, shown in Fig. 5, said lugs being so positioned that either 100 may be conveniently held with a finger of a person's hand grasping the book, while the pamphlet is being withdrawn with his other hand from the pamphlet clamping devices of the holder.

105 The invention and the manner of using the same will, it is thought, be understood from the foregoing description of the illustrated embodiment of the invention now preferred by me. While I have illustrated and described a preferred embodiment of the invention, I do not wish to be understood as confining myself specifically thereto except as I may be limited by the following claims.

110 What I claim, is,—

115 1. In a book supported reference pamphlet

120

- phlet holder, a pair of plate members each provided with a head portion and two spaced apart book engaging fingers depending therefrom, clamping plates cooperating with the respective members for clamping a pamphlet to the holder, springs for actuating said clamping plates, screw devices engaging said members for regulating the effective power of said springs, and an extensible link hingedly connected to the head portions of the respective members for retaining the latter in selected spaced apart relation.
10. In a book supported reference pamphlet holder, a pair of plate members each provided with a head portion and two spaced apart book engaging fingers depending therefrom, clamping plates cooperating with the respective members for clamping a pamphlet to the holder, springs for actuating said clamping plates, screw devices for regulating the effective power of said springs, and an extensible link hingedly connected to the head portions of the respective members for retaining the latter in selected spaced apart relation.

15. In a book supported reference pamphlet holder, a pair of plate members each provided with a head portion and two spaced apart book engaging fingers depending therefrom, clamping plates cooperating with the respective members for clamping a pamphlet to the holder, springs for actuating said clamping plates, screw devices for regulating the effective power of said springs, and an extensible link hingedly connected to the head portions of the respective members for retaining the latter in selected spaced apart relation.
20. In a book supported reference pamphlet holder, a pair of plate members each provided with a head portion and two spaced apart book engaging fingers depending therefrom, clamping plates cooperating with the respective members for clamping a pamphlet to the holder, springs for actuating said clamping plates, screw devices for regulating the effective power of said springs, and an extensible link hingedly connected to the head portions of the respective members for retaining the latter in selected spaced apart relation.
25. In a book supported reference pamphlet holder, a pair of plate members each provided with a head portion and two spaced apart book engaging fingers depending therefrom, clamping plates cooperating with the respective members for clamping a pamphlet to the holder, springs for actuating said clamping plates, screw devices for regulating the effective power of said springs, and an extensible link hingedly connected to the head portions of the respective members for retaining the latter in selected spaced apart relation.

30. In a book supported reference pamphlet holder, a pair of plate members each provided with a head portion and two spaced apart book engaging fingers depending therefrom, clamping plates cooperating with the respective members for clamping a pamphlet to the holder, springs for actuating said clamping plates, screw devices for regulating the effective power of said springs, and an extensible link hingedly connected to the head portions of the respective members for retaining the latter in spaced apart relation.
35. In a book supported reference pamphlet holder, a pair of plate members each provided with a head portion and two spaced apart book engaging fingers depending therefrom, clamping plates cooperating with the respective members for clamping a pamphlet to the holder, springs for actuating said clamping plates, screw devices for regulating the effective power of said springs, and an extensible link hingedly connected to the head portions of the respective members for retaining the latter in spaced apart relation.

40. In a book supported reference pamphlet holder, a pair of plate members each provided with a head portion and two spaced apart book engaging fingers depending therefrom, clamping plates cooperating with the respective members for clamping a pamphlet to the holder, springs for actuating said clamping plates, screw devices for regulating the effective power of said springs, and an extensible link hingedly connected to the head portions of the respective members for retaining the latter in spaced apart relation.
45. In a book supported reference pamphlet holder, a pair of plate members each provided with a head portion and two spaced apart book engaging fingers depending therefrom, clamping plates cooperating with the respective members for clamping a pamphlet to the holder, springs for actuating said clamping plates, screw devices for regulating the effective power of said springs, and an extensible link hingedly connected to the head portions of the respective members for retaining the latter in spaced apart relation.
50. In a book supported reference pamphlet holder, a pair of plate members each provided with a head portion and two spaced apart book engaging fingers depending therefrom, clamping plates cooperating with the respective members for clamping a pamphlet to the holder, springs for actuating said clamping plates, screw devices for regulating the effective power of said springs, and an extensible link hingedly connected to the head portions of the respective members for retaining the latter in spaced apart relation.

55. A pamphlet holder comprising a pair of plate members each having a head portion and depending spaced fingers adapted to straddle leaves of a book, an extensible link having the ends thereof hingedly connected to the head-portions of said members to adapt the same for movement with the covers of a book, and clamp-parts pivotally and yieldably mounted upon the head-portions of said members and adapted to engage leaves of a pamphlet with the holder.
60. In a holder of the class described, a pair of horizontally spaced apart holding

members each comprising a head-portion, a clamp-plate yieldably mounted thereon, and dependent spaced apart and relatively offset fingers integral with the respective head portions, and an extensible link pivotally connected to the head-portions of the respective members.

Signed at Seattle, Washington, this 17th day of March, 1928.
